CLAIM

The ornamental design for a relay retaining bracket, as shown in the accompanying drawings.

DESCRIPTION

FIG. 1 is a perspective view of the design of a relay retaining bracket in accordance with the present invention as seen looking toward the top and right front corner.

FIG. 2 is a rear elevational view of the relay retaining bracket in accordance with the present invention.

FIG. 3 is a right side elevational view of the relay retaining bracket in accordance with the present invention.

FIG. 4 is a front elevational view of the relay retaining bracket in accordance with the present invention.

FIG. 5 is a left side elevational view of the relay retaining bracket in accordance with the present invention.

FIG. 6 is a top plan view of relay retaining bracket in accordance with the present invention as seen from the rear; and, FIG. 7 is a bottom view of the design in accordance with the present invention.
